UNITED STATES PATENT OFFICE.

CHARLES E. WAREAM, OF CINCINNATI, AND DANA H. BENJAMIN, OF CLEVELAND HEIGHTS, OHIO, ASSIGNEES TO THE AMERICAN LAUNDRY MACHINERY COMPANY, OF NORWOOD, OHIO, A CORPORATION OF OHIO.

SHIRT-FOLDING TABLE.

1,351,079.

Specification of Letters Patent. Patented Aug. 31, 1920.

Application filed July 24, 1918. Serial No. 246,506.

To all whom it may concern:

Be it known that we, CHARLES E. WAREAM and DANA H. BENJAMIN, citizens of the United States, residing at Cincinnati and Cleveland Heights, respectively, in the counties of Hamilton and Cuyahoga and State of Ohio, have invented certain new and useful Improvements in Shirt-Folding Tables, of which the following is a specification.

This invention relates to folding tables for use in folding shirts.

In the manufacture of shirts it is the custom, after the shirt is ironed, to fold it up in well known form with the tail portions wrapping and inclosing the sleeves, the bosom portion being exposed in flat form. The dress of the shirt or its appearance when folded is an important factor in the price it commands.

Heretofore, these shirts have been folded on a table by first laying the shirt on the table with its bosom uppermost so as to arrange said bosom and apply finishing touches thereto with a hand iron, after which the shirt is carefully turned over and folded on a form.

The object of the present invention is to provide improved apparatus for assisting in the folding operation, which insures the best dress and set up for the shirt and enables the operator to produce a symmetrical arrangement and at the same time avoid wrinkles, and which is of simple construction and is easily manipulated so that the output of the operator is increased.

Further objects of the invention are in part obvious and in part will appear more in detail hereinafter.

The invention comprises the construction and arrangement of parts hereinafter described and claimed.

In the drawings, which represent one embodiment of the invention, Figure 1 is a plan view, the folding form being depressed into operating position; Fig. 2 is a front elevation, partly in section on the line 2-2, Fig. 1, and showing the folding form elevated, part thereof being broken away for convenience in illustration; Fig. 3 is a sectional elevation on the line 3-3, Fig. 2; Fig. 4 is a plan view, on a larger scale, illustrating the expandible neckband former expanded to a large size; Fig. 5 is a cross sec-

tion thereof on the line 5-5, Fig. 4, looking in the direction of the arrows; and Fig. 6 is a side elevation of the neckband expander.

The apparatus shown in the drawings comprises a suitable table or support consisting of a bed or body 1 mounted on columns or legs 2 and preferably provided with a layer 3 of suitable padding. At one end of the table is a shelf 4 for supporting hand irons or other devices used in connection with the table, while at its other end and at a lower level is a shelf 5 upon which the folded or unfolded shirts can be piled.

Near one end of the table the padding on its upper surface is cut away and the table body 1 is also counter-sunk or recessed to provide a cavity 6 having a large portion shaped to correspond with the neckband of a shirt and as large or slightly larger than the largest size of shirt, said cavity also having a longitudinally extending narrow slot 7. The padding around the edges of this recess or cavity is protected by a shield or guard 8, which is a comparatively thin metal member extending around the edges of the cavity and provided with a horizontal flange 9 overlying the padding. Said guard may be held down by screwing up the nuts 10 on bolts 11 carried by the guard and passing through openings in the bed and may be further secured, if desired, by driving a number of pins 12 down through the guard and padding into the wooden bed.

The larger portion of the recess or cavity 6 in the bed contains an expandible neckband former of any suitable form which is expanded into the neckband of the shirt when the latter is applied to the table. The drawings show for this purpose a former comprising a stationary body portion 13 provided with a depending bolt 14 passing through an opening in the bed and secured thereto by a nut 15 on its lower end. This stationary body portion is provided with guide ways for a series of movable members, the movement of which along said guide ways enables the former to be expanded or contracted, as desired. The expanding portions of the neckband former include a front portion 16 curved to fit the front and side portions of the neckband and having a recess 17 in its front to receive the front collar button. This front member of the former has a base or body provided with a

22
 T slot to receive the guiding T rib 19 of the base 13 along which member 16 slides. It also carries one or more, two being shown, of depending pins 20, which pass through 5 elongated openings in the base 13 and slots 22 in the bed 1, said pins extending below the bed 1 as shown in Fig. 2.

The rear portion of the neckband former includes two rear adjustable members 23 10 having T slots to receive laterally extending T ribs 24 on the base 13, so that said members have lateral movement toward and from each other on the base. Each of said members is connected by a link 25 to the short arm of a bell crank lever 26 pivoted at 27 upon the base 13, the longer arms of the two levers 26 having curved slots 28 to receive a pin 29 carried by the front member 16 of the neckband former. The arrangement is such that as the front member 16 is moved back and forth along its guide ways on the base 13 it turns the bell crank levers 26 and produces corresponding movement of the two members 23 inwardly and outwardly on the base. Movement of the front portion of the neckband former therefore produces expanding or contracting movement of all of the movable members of the former.

The depending pins 20 are secured at their 30 lower ends in a member 30 connected to one end of a rod 31 having sliding movement in guides 32 carried by the bed. Said rod is also provided with a collar 33 forming an abutment for a pressure spring 34 lying between said collar and one of the guides 32. Collar 33 may be adjusted length-wise on the rod 31 to vary the pressure of said spring, being held in adjusted position in any suitable manner such as by the set screw 34. 35 Member 30 is also provided with a depending arm or yoke 35 connected by a short link 36 to an arm 37 on a shaft 38 having turning movement in a bracket 39 carried by the bed, said shaft being also provided with a second 40 arm 40 connected by a link 41 to an arm 42 on a shaft 43 extending longitudinally of the table and having turning movement in the legs or supports therefor. Between said legs shaft 43 supports a treadle 44, which 45 may be of any suitable form and is shown as a rather long wide plate carried by arms 45, so as to enable the mechanism to be operated from practically any position in which the operator may stand.

50 It will be observed that the tendency of the pressure spring 34 is to move the rod 31 to the right in Fig. 2 thereby expanding the neckband former. Downward pressure on the treadle 44 through the link and lever 55 mechanism described moves the rod 31 to the left against the pressure of said spring to contract the neckband former. Obviously however the neckband former may be both opened and closed by lever mechanism

or may be normally contracted by a spring 65 and expanded by lever mechanism.

In use of the apparatus the operator contracts the former and applies the shirt to the table with the bosom down, inserting the neckband into the recess 6 of the table and 70 with said neckband surrounding the neckband former. The buttons of the shirt are then pressed downwardly to introduce them into the shallow channel 46 of the guard 8 thereby locating the shirt on the table with 75 its longitudinal or center line parallel with the edges of the table. The foot is then removed from the treadle and the spring 34 expands the neckband former into the neckband of the shirt. The operator can now 80 straighten out the shirt upon the table and with a hand iron apply the finishing touches when such are necessary.

To assist in folding up the shirt the operator may apply thereto the form around 85 which the shirt is folded. This form may be a loose rectangular metal sheet, but preferably said form is attached to the table in such manner that it can be readily moved into and out of operative position and is so 90 located on the table with reference to the recess therein as to cause the shirt to be folded into symmetrical form. The drawings show for this purpose a rectangular plate 47 attached to two arms 48 connected 95 to a transverse shaft or rod 49 carried by two brackets 50 secured to the table, this arrangement enabling the form to be turned downwardly to the position shown in Fig. 1 or elevated to the position shown in Fig. 2, so 100 as to expose the recess in the table and enable a shirt to be applied thereto. Preferably the arms 48 are provided with feet 51 which contact with the padding when the form is elevated and support it in its upper position. 105

After the shirt has been applied to the table and the former expanded therein, as before described, the form 47 is dropped down upon the shirt and the shirt is then folded up around the form and fastened in 110 its final form by pins or other devices as is usual. The operator then depresses the treadle 44 to contract the neckband former and release the shirt, which is raised with the form 47 and then slipped off from the 115 form, as will be readily understood.

The construction described enables the shirt to be rapidly and uniformly folded in symmetrical form and thereby reduces the cost of shirt manufacture. The invention, 120 of course, is adapted for use in laundries for folding up laundered shirts.

What we claim is:

1. A shirt folding table, including a shirt receiving bed provided with a recess, and 125 an expansible neck band former in said recess.

2. A shirt folding table, including a shirt

- receiving bed provided with a recess, an expandible neck band former in said recess, and operating mechanism therefor.
3. A shirt folding table, including a shirt receiving bed provided with a recess, an expandible neck band former in said recess, and operating mechanism therefor, located below said bed.
4. A shirt folding table, including a shirt receiving bed provided with a recess, an expandible neck band former in said recess, means normally adjusting said former to one size, and operating mechanism for adjusting the same to another size.
5. A shirt folding table, including a shirt receiving bed provided with a recess, an expandible neck band former in said recess, yielding means normally adjusting said former to one size, and operating mechanism for adjusting the same to another size.
6. A shirt folding table, including a shirt receiving bed provided with a recess, and an expandible neck band former in said recess, said recess having a button receiving slot.
7. A shirt folding table, including a shirt receiving bed provided with a recess, an expandible neck band former in said recess, and a guard for the edges of said recess.
8. A shirt folding table, including a shirt receiving bed provided with a recess, an expandible neck band former in said recess, said recess having a button receiving slot, an expandible neck band former in said recess, and a guard for the edges of said recess.
9. A shirt folding table, including a shirt receiving bed provided with a recess, an expandible neck band former in said recess, and a shirt receiving form coöperating with said bed.
10. A shirt folding table, including a shirt receiving bed provided with a recess having a large portion and a narrow button receiving portion, an expandible neck band former in the larger portion of said recess, and a shirt receiving form coöperating with said bed and adapted to substantially cover both portions of said recess.
11. A shirt folding table, including a shirt receiving bed provided with a recess, an expandible neck band former in said recess, and a shirt receiving form movably supported and adapted to be moved into and out of a position overlying said recess.
12. A shirt folding table, including a shirt receiving bed provided with a recess, an expandible neck band former in said recess, and a shirt receiving form hinged to the bed at the neck band end of said recess.

In testimony, whereof we affix our signatures.

CHARLES E. WAREAM.
DANA H. BENJAMIN.
